UNITED STATES PATENT OFFICE.

MARCUS O. ANTHONY, OF ENGLEWOOD, NEW JERSEY, AND JOSEPH E. O'DONNELL, OF BROOKLYN, NEW YORK, ASSIGNEES TO A. KIMBALL COMPANY, OF NEW YORK, N. Y., A CORPORATION OF NEW YORK.

PIN-TICKET MACHINE.

1,292,224.

Specification of Letters Patent. Patented Jan. 21, 1919.

Application filed January 4, 1915. Serial No. 476.

To all whom it may concern:

Be it known that we, MARCUS O. ANTHONY, a citizen of the United States, and resident of Englewood, county of Bergen, State of New Jersey, and JOSEPH E. O'DONNELL, a citizen of the United States, and resident of Brooklyn, county of Kings, State of New York, have invented an Improvement in Pin-Ticket Machines, of which the following description, in connection with the accompanying drawing, is a specification, like characters on the drawing representing like parts.

This invention relates to improvements in consecutive wire feeding mechanism for pin-ticket machines, staple forming machines, and like machines which are adapted to form or manufacture wire blanks of predetermined lengths.

20 The invention is disclosed herein as adapted to a machine for making pin-tickets or tags known as the "Empire" ticket in which the ends of a fastener in the form of a staple is inserted in the cardboard composing the 25 tag adjacent to one edge thereof, and the loop of the staple bent over and around the edge of the card to fasten the staple firmly to the card and maintain it in position when the card is affixed to the merchandise.

30 In machines of this character heretofore constructed the staple has been formed automatically in the machine from a wire fed in front of the staple forming device and severed just before the former advances to 35 bend the wire into staple form.

The severing device in such machines usually cut the wire at an angle to its axis so that the pin points are not disposed axially of the legs of the staple, furthermore in thus 40 severing the wires a roughened edge is left upon the tapered portion and often a bur is formed upon the point.

When staples of this character are inserted in delicate fabrics the burs and 45 rough edges engage the fibers of the threads of which the material is made and draw them out thus leaving an objectionable snagged spot in the fabric.

The object of the present invention is to 50 provide means for feeding previously prepared wire blanks or pins of predetermined

length to the staple forming and setting mechanism so that the completed pin ticket will be free from the objections above noted. In order to accomplish this object we have 55 devised a novel form of wire blank feeding mechanism and have illustrated the same as applied to the machine which is commercially known as the "Empire" machine and which is disclosed in Patent No. 457,782 60 granted Aug. 18, 1891, to Alonzo Kimball.

This feeding mechanism comprises a hopper with suitable mechanism attached thereto adapted to deliver pins of the proper length one at a time to the staple forming 65 mechanism of the "Empire" machine aforesaid. It is to be understood however that this blank feeding mechanism may be adapted and applied to staple forming machines of other types within the contemplation of 70 our invention as set forth in the claims here-to annexed.

In the drawings:

Figure 1 is a vertical transverse sectional view through the forming and setting mechanism of the "Empire" machine illustrated in the Kimball Patent No. 457,782, this view corresponding to Fig. 17 of the patent aforesaid and showing the present invention applied thereto,

80 Fig. 2 is a front elevation of the pin supporting and feeding mechanism, the hopper being omitted therefrom,

Fig. 3 is a detail vertical sectional view of the gate which retains the pins within 85 the feeding mechanism until the lowermost pin is engaged by the staple forming plunger, and

Fig. 4 is a horizontal sectional view on lines 4-4, Fig. 2 looking downward and 90 illustrating in dotted lines the staple forming plunger engaging the lowermost pin.

The bed plate of the pin ticket machine as illustrated in the drawing comprises an inverted box-like construction 1 resting upon 95 a suitable base 2 and having an upwardly offset portion 3, to the upper face of which is secured a guide strip 4 having an undercut groove 5 adapted to receive and direct a strip of cardboard 6 which is to be cut 100 into lengths to form the pin tickets. It will be understood that the cardboard may be

and usually is printed as desired before it reaches the staple forming and setting mechanism.

A plate 7 having a groove 8 located adjacent to the inner end of the offset portion 3 of the bed plate forms a way or channel in which the ends of the staples may travel after they have been set in the cardboard, as the cardboard strip is advanced.

- 10 In the usual form of the "Empire" machine the wire is led in front of the end of a plunger or former 9 which is in effect a die coöperating with the bifurcated end of a plate 10 which forms the other member 15 of the die and serves upon the forward movement of the die plunger 9 to bend the blank into U-shaped form carrying the bent end of the staple over a movable support 11 so that the staple will rest temporarily upon 20 the support. The former 9 desirably is actuated through a lever 12 pivotally secured to a bracket 13 on the former 9, said lever being pivoted intermediate its ends upon a stud 14 carried by a suitable bracket 15 supported from the frame of the machine. The upper end of the lever 12 is provided with an anti-friction roller 15 which engages a cam groove 16 in a cam disk 17 suitably mounted upon a shaft 18 extending longitudinally of the machine.

The shaft 18 may be conveniently actuated through a countershaft 19 connected by suitable gearing, not shown herein, to the main driving shaft 20 which is journaled 35 upon the opposite side of the longitudinal center of the machine. Suitable mechanism is provided for bending the staple above described transversely and inserting the same near the edge of the pin ticket and finally 40 bending the looped portion of the staple beneath and under the edge of the pin ticket. This mechanism desirably comprises a pair of parallel plungers 21, 22 slidably mounted in ways in a guide 23, the upper ends of 45 said plungers being secured to a lever 24 pivoted upon a stud 25 carried by a bracket 26 supported upon a stand 27 rising from the bed plate 1. The opposite edge of the lever 24 is provided with an anti-friction 50 roller 28 which engages a cam groove 29 in a cam disk 30 suitably secured upon the shaft 20. The downward reciprocation of the parallel plungers 21, 22 serves to bend the staple about the support 11 so that the 55 ends of the staple are presented to the blank for the pin ticket at a short distance back from the edge thereof, and the loop of the staple is bent vertically downward.

A supplemental plunger 31, slidably 60 mounted between the plungers 21-22 and which is actuated through a lever 32 from a cam (not shown) upon the cam disk 30, is arranged to descend upon the staple after the staple has been bent in the manner 65 aforesaid and drive the same through the

pin ticket blank, the support 11 having in the meantime been withdrawn by suitable mechanism not shown herein but which is fully disclosed in the Kimball patent aforesaid.

When the staple has thus been inserted in the pin ticket blank the looped end of the staple is bent under the edge of the blank to firmly secure the staple to the same with its legs projecting at right angles to the under surface of the blank. This is accomplished by means of a plunger 33 pivotally attached to a plunger arm 34 which is slidably mounted in a guiding member 35 resting on the base 1. The plunger arm 34 desirably is reciprocated through a lever 36 pivotally connected to a bracket 37 upon the end of the plunger arm 34, said lever being pivoted at its central portion upon a stud 38 carried by a suitable bracket 39 supported from the machine frame. The upper end of the lever is actuated to reciprocate the plunger 33 by a disk 40 secured upon the shaft 20 and having a cam projection 41 adapted to engage the side of the lever 36, the lever being retained normally in retracted position by a helical spring 42 secured to the upper end of the lever 36 and anchored to the frame.

The pivoted end portion 33 of the plunger 95 is provided on its underside with a recess 43 having a beveled shoulder 44 adapted to engage a wedge shaped member 45 so that the end of the plunger 33 will be raised slightly as it carries the loop of the staple 100 under the strip of cardboard thereby bringing the loop of the staple in close contact with the back of the cardboard blank and between the prongs of the staple, thus locking the staple firmly upon the card. The 105 end of the plunger 33 is normally held down by a leaf spring 46 which is affixed to the guide 35 and has its free end bearing upon the upper surface of the plunger 33. During the operation of the horizontal plunger 110 33 the strip of cardboard together with the inserted staple is sustained by an abutment 47 which is moved by suitable mechanism over the upper portion of the cardboard and receives the upward thrust or pressure of the 115 plunger 33. The mechanism thus described is of the usual construction of the "Empire" pin ticket machine as disclosed in the Kimball patent aforesaid.

In the present invention we have substituted for the wire feeding mechanism disclosed in that patent, means for feeding a series of blanks, preferably double pointed, to the staple forming and setting mechanism. This feeding mechanism may conveniently be secured to the front face of the stand 27 and comprises a preferably vertical guideway formed of relatively reciprocable members, which as shown herein includes a rear vertical plate or member 50 120

having a bifurcated lower end 50^a, 50^b, and a similar forward parallel member 51, one or both of said members being provided with a groove 52 of just sufficient depth to permit the double pointed blanks to drop freely therethrough and of sufficient width to accommodate blanks of suitable length to form pin ticket staples.

The member 50 may be secured to the stand 27 in any suitable manner. As illustrated herein the stand 27 is provided with laterally extending ears 53 to which are pivoted turn buttons 53^x which are adapted to overlap and engage the front face of projections 54 extending upwardly from the face of the rear plate 50. The lower ends 50^a and 50^b of the rear plate are provided with lips 55 which extend forwardly and form supports at the lower end of the guideway 52 which prevent the pins from dropping out. The front plate 51 is slidably mounted upon the stationary plate 50, preferably by means of a series of screws 56 which may be arranged at convenient distances along the sides of said plate 50 passing through suitable recesses 57 in the plate 51. The edges of the plate 51 are also provided with recesses 58 adapted to receive the projections 54 of the rear plate 50, the recess 58 being of such size and the walls thereof so disposed as to limit the upward and downward movement of the plate 51 relative to the plate 50.

A bracket or plate 59 secured to the upper end of the plate 50 by screws 60 or other suitable fastenings serves to support a hopper 61 adapted to deliver pins into the guideway between the plates 50 and 51 above described.

In order to insure the constant delivery of blanks from the bottom of the guideway it is desirable to reciprocate the plate 51 rapidly during the operation of the machine. This is accomplished in the present instance through a lever 62 having a forked end 63 engaging a stud 64 in a bracket 65 secured centrally to the front face of the plate 51, said lever 62 being connected at its other end to a pivot 66 upon the upper end of a stand 67 secured to the frame of the machine in any suitable manner. The lever 62 is so arranged that its central portion rests upon a disk 68 secured to the shaft 18, said disk having on its edges a series of preferably three relatively small projections or cams 69 which when contacting with the under face of the lever 62 serve to reciprocate slightly the plate 51, and a single cam 70 which projects higher than the cams 69 and is so timed as to raise the plate 51 a maximum distance at the time the forming plunger 9 advances to engage the lowermost pin in the guideway to carry it to the staple forming mechanism.

In order to prevent pins from spilling out

at the bottom of the guideway when the plate 51 is thus raised we have provided a central gate 71 which is slidably mounted upon the forward plate 51 by means of screws 72 passing through a suitable slot 73 in said gate and anchored in the plate 51. The gate desirably is provided at its upper end with a stem 74 which passes through a lug 75 upon the front face of the central portion of the plate 51. A helical spring 76 interposed between the lug 75 and the upper end of the gate slide 71 serves to retain the gate normally depressed to the upper plane of the lips 55 of the rear plate 50 notwithstanding the vibration of the plate 51. The lower end of the plate 71 is bent to present an inclined outer face 77, and an inner flat face 78 adapted to engage the pins or blanks which are located at the lowermost end of the guideway 52.

The inclined surface 77 of the gate is engaged by the forward end of the plunger 9 when the latter is reciprocated to engage the lowermost pin in the guideway or chute and upon the further advancement of said plunger the gate is raised sufficiently to permit the plunger 9 to pass beneath the same to engage the lowermost blank or pin and carry it to the staple forming mechanism in the manner heretofore described. As the plunger advances the lowermost blank is carried between the forked lower ends 50^a and 50^b of the plate 50 and is partially bent into the form of a staple. Upon further advancement the plunger 9 carries the partially bent staple between the guides or dies of the staple forming mechanism above described which serves to bend the staple into its completed U-shaped form. Thereupon the plungers 21 and 22 descend and bend the staple transversely about the support 11. When this is accomplished the plunger 31 descends and drives the staple through the cardboard, the support 11 having in the meantime been removed. As soon as the staple has passed through the cardboard the plunger 43 is advanced and raised to first bend the loop of the staple beneath the cardboard and secondly to force the loop firmly against the under portion of the cardboard between the legs of the staple, thus fastening the staple firmly to the cardboard.

It will be observed that in the operation of this machine the ends of the staple blanks are not engaged by any metallic members so that perfectly pointed blanks may be utilized and may be inserted in the card without fear of destroying the points or tips of the staples. By means of this construction, therefore pin tickets having staples with perfect points can be furnished which will be free from the objection of roughness or burs upon the pins of the character above described.

It is to be understood that the feeding

mechanism herein described is illustrative of the invention but not restrictive thereof and that the same may be embodied in various other forms or may be utilized with other 5 types of wire forming machines within the meaning and the scope of the following claims.

Having fully described our invention, what we claim as new and desire to secure 10 by Letters Patent is:

1. A pin ticket machine comprising staple forming mechanism including a reciprocating forming plunger and means coöperating therewith to form a staple, a hopper for 15 the staple blanks, a guideway leading from said hopper to said staple forming mechanism adapted to present the blanks successively transversely of the path of said forming plunger, and means for retaining 20 said blanks in said guideway operable by said forming plunger to permit the latter to remove the lowermost blank.
2. In a pin ticket machine comprising staple forming mechanism including a reciprocating forming plunger; a hopper for 25 the staple blanks, a guideway leading from said hopper to the staple forming mechanism and adapted to direct a series of superposed blanks to said staple forming mechanism, and means for retaining the staples 30 in said guideway including means reciprocably actuated by said plunger to permit said plunger to remove the lowermost staple from said guideway.
3. In a machine of the class described, 35 blank feeding mechanism comprising a plurality of relatively movable members having a guideway between them to receive a plurality of superimposed blanks arranged in parallelism, means for causing relative movement of said members, and means for engaging the ends only of the lowermost blank whereby the central portion thereof will be exposed to permit its removal laterally from said guideway.
4. In a machine of the class described, 45 blank feeding mechanism comprising a pair of vertically arranged parallel guiding members having a recess therebetween adapted to receive a series of superposed parallel blanks, means for causing relative reciprocation of said members in parallelism and means for engaging the ends only of the lowermost blank whereby the central portion thereof will be exposed to permit its removal laterally of said guideway.
5. In a machine of the class described, 55 blank feeding mechanism comprising a hopper, a recessed member leading from said hopper adapted to form a guideway for a series of parallel superposed blanks, and having a bifurcated lower end provided with lips adapted to arrest the lowermost blank, a parallel member slidably mounted

upon said recessed member and means for 65 reciprocating said slidable member.

6. In a machine of the class described, blank feeding mechanism comprising a hopper, a longitudinally recessed member leading from said hopper adapted to form 70 a guideway for a series of parallel superposed blanks, and having a bifurcated lower end provided with lips adapted to arrest the lowermost blank, a parallel member 75 slidably mounted upon said recessed member, a lever pivotally connected to said slidable member, and means for oscillating said lever.

7. In a machine of the class described, blank feeding mechanism comprising a 80 hopper, a longitudinally recessed member connected to said hopper adapted to form a guideway for a series of parallel superposed blanks, a parallel member slidably mounted thereon, a lever pivotally connected 85 to said slidable member, means for oscillating said lever including a disk having a series of cams adapted to engage successively the lever intermediate of its connection to said slidable member and its fulcrum, and means for rotating said cam.

8. In a machine of the class described, feeding mechanism comprising a hopper a stationary plate leading therefrom and having lips at its lower end, a plate slidably mounted on said stationary plate, one of said plates being recessed to form a guideway for blanks arranged in parallelism, means for reciprocating said slidable plate and means yieldably supported in co-operative relation to said lips for retaining normally the lowermost blank in said guideway during the reciprocation of the slid- 95 able plate.

9. In a machine of the class described, feeding mechanism comprising a hopper, a stationary plate provided with a longitudinal recess leading from said hopper and forming a guideway for blanks arranged in parallelism, and with lips at its lower end, a plate slidably mounted upon said stationary plate, means for reciprocating said slid- 100 able plate, and means connected to said slidable plate for retaining the lowermost blank in said guideway.

10. In a machine of the class described, feeding mechanism comprising a hopper, a stationary plate recessed longitudinally to form a guideway leading from said hopper, a plate slidably mounted upon said stationary plate, means for reciprocating said slid- 110 able plate, a spring pressed gate slidably mounted upon said slidable plate and arranged normally to retain the lowermost blank in said guideway.

11. A pin ticket making machine comprising staple forming mechanism including a horizontal reciprocating plunger, a hop-

- per, a stationary plate leading from said hopper to said staple forming mechanism and provided with a longitudinal recess adapted to form a guideway for a series of 5 blanks disposed in parallelism, a plate slidably mounted upon said stationary plate, a gate slidably mounted upon said sliding plate, means for actuating said sliding plate comprising a disk having a series of low 10 cams adapted to reciprocate said sliding plate to agitate the blanks in the guideway and a high cam adapted to raise said sliding plate to deliver a blank to the staple forming mechanism; and means for actuating 15 said plunger simultaneously with the raising of the gate to cause said plunger to engage the lowermost staple in the guideway.
12. In a pin ticket making machine comprising staple forming and setting mechanism including a horizontally reciprocating plunger; a hopper, a recessed plate forming a guideway leading to said staple forming mechanism and having a bifurcated lower end provided with laterally extending lips, 20 a plate slidably mounted on said recessed plate, a spring pressed gate mounted upon said sliding plate and having an inwardly offset lower end adapted to coöperate with the lips upon said recessed plate to retain 25 the lowermost blanks in said guideway and presenting an outward inclined surface, means for reciprocating said sliding plate and for simultaneously advancing said plunger whereby the forward end of said 30 plunger will engage the inclined surface of said gate and raise the same permitting the end of the plunger to engage and bend the lowermost blank between the bifurcated ends of the recessed plate.
- 35 13. In a machine for making pin tickets, a staple forming mechanism including a horizontally reciprocating staple forming plunger and a vertically reciprocating setting plunger and means for actuating the 40 same, blank feeding mechanism comprising a hopper consisting of two relatively reciprocable members having a longitudinally extending recess therebetween forming a 45
- guideway leading from said hopper and arranged to present said blanks transversely 50 of the path of said forming plunger and quickly operable locking means, detachably securing said blank feeding mechanism in operative relation to the staple forming mechanism whereby said feeding mechanism 55 may be readily removed and replaced.
14. In a pin ticket machine, a staple forming mechanism including a horizontally reciprocating forming plunger, a stand having a vertically reciprocating staple setting 60 mechanism, a hopper comprising a stationary and a reciprocable plate having a guideway therebetween, means for detachably securing said hopper to said stand to position the end of said guideway transversely 65 of the path of reciprocation of the forming plunger, and means for retaining the lowermost blank in said guideway in the path of said forming plunger whereby the reciprocations of the plunger will successively remove the lowermost blank.
15. In a pin ticket machine having horizontal staple forming mechanism, a vertically operable staple bending and setting mechanism, means for supporting and guiding 70 said vertically operating mechanism, a hopper, a guideway leading from said hopper to said staple forming mechanism composed of a stationary and a reciprocable plate having a guideway therebetween 75 adapted to receive a plurality of superposed blanks; means for detachably securing said guideway to the support for said vertically operating staple setting mechanism comprising ears extending laterally from said support, and members pivotally mounted thereon adapted to overlie retaining projections upon said guideway.
- In testimony whereof we have signed our names to this specification in the presence of 80 two subscribing witnesses.
- MARCUS O. ANTHONY.
JOSEPH E. O'DONNELL.
